UNITED STATES PATENT OFFICE.

JESSE I. RICE, OF NEW YORK, N. Y.

DESIGN FOR A HAIR-DRESSING COMB.

No. 40,077.

Specification for Design.

Patented June 22, 1909.

Application filed April 15, 1909. Serial No. 490,182. Term of patent 3½ years.

To all whom it may concern:

Be it known that I, JESSE I. RICE, a citizen of the United States, residing at New York, county and State of New York, have invented a new, original, and ornamental Design for a Hair-Dressing Comb, of which the following is a specification, reference being had to the accompanying drawings, forming part thereof.

Figure 1 is a plan view of the hair dressing comb, and Fig. 2 is a perspective view of the same.

The hair dressing comb of this design consists of two sets of comb teeth *a*, *a* connected together by two bars *b*, *b*, constituting the band, and are arranged in different planes passing in flatwise direction through the comb and the whole is formed curvilinearly

with the free ends, near which the comb teeth are located, closer together than the largest or main diameter, as shown in plan at Fig. 1. The bars *b*, *b* are connected together at intervals by ornamental or decorated pieces *c*, *c*. The teeth *a*, *a* extend from the lower edge at the side parts of the device and the side parts *d*, *d* are turned toward a plane so as to be flatter than the band or main portion of the device.

I claim,

The ornamental design for a hair dressing comb as shown and described.

JESSE I. RICE.
